UNITED STATES PATENT OFFICE.

OTTO G. HITCHCOCK, OF ERIE, PENNSYLVANIA, ASSIGNOR TO HAYS MANUFACTURING CO., OF ERIE, PENNSYLVANIA, A CORPORATION OF PENNSYLVANIA.

DESIGN FOR A MIXING FAUCET.

Application filed April 19, 1922. Serial No. 1,847. Term of patent 14 years.

To all whom it may concern:

Be it known that I, Otto G. Hitchcock, a citizen of the United States, residing at Erie, in the county of Erie, and State of Pennsylvania, have invented a new, original, and ornamental Design for Mixing Faucets, of which the following is a specification, reference being had to the accompanying drawing, forming part thereof.

The figure is a perspective view of a mixing faucet, showing my new design.

I claim:

The ornamental design for a mixing faucet, as shown.

OTTO G. HITCHCOCK.
